OILSTOVE

Charles J. Kessler, Cleveland Heights, and Joseph R. Kirkpatrick, South Euclid, Ohio, assignors to Perfection Stove Company, Cleveland, Ohio, a corporation of Ohio

Application October 15, 1937, Serial No. 169,218

7 Claims. (Cl. 158—91)

This invention relates to oilstoves of the class in which the oil is fed to the bottom of a burner bowl where it is vaporized and burned in the presence of air admitted to the bowl through primary and secondary air inlets from a space below and about the bowl. The rate of flow of the oil and consequently the size of the fire are controlled by a suitable valve; and to avoid overflow or undue flooding of the bowl, especially when the fire is out and the valve is open, liquid level control means is employed.

The burner bowl, in the type of stove where-with we have shown our improvements associated and to which they are peculiarly applicable, has a relatively large lateral opening through which, upon removal of a closure, access may be had to the interior of the bowl for lighting and cleaning purposes.

Inasmuch as vaporization of the oil is dependent very largely upon heat being conducted to the oil from the flame above through the side and bottom walls of the bowl, it is essential that these walls be maintained at high temperature while the stove is in normal operation, and that they attain such high temperature as soon after the fire is started as possible in order that combustion may be quickly advanced to a satisfactory stage.

It is a well known fact that the heavier or less volatile the oil is, the greater is the heat required to vaporize it. Heretofore, burners of the class under consideration have been designed to operate efficiently and satisfactorily on an oil of a given grade or volatility, and any appreciable deviation from the prescribed grade, especially in the direction of heavier oils of less volatility, resulted in inferior operation.

In order to adapt a single stove to oils of different grades, a vaporization control was invented by Lee S. Chadwick and one of the present applicants, Charles J. Kessler, as disclosed in their application Serial No. 138,168, filed April 21, 1937, in which a regulator is employed for varying the temperature of the burner bowl to meet the different vaporization requirements of light, medium and heavy oils. Through indifference to directions on the part of the users, failure to identify the grades of oils, or other causes, the invention just mentioned cannot be relied upon to solve the problem presented by the different kinds of oils available to stove users.

Looking toward a solution of the difficulty, it is the primary purpose of the present invention to provide a stove of the aforesaid class that will, without change or adjustment, operate effi-

ciently, economically and satisfactorily on all grades of oil within a practical range, producing approximately complete combustion, and consequently a clean fire; and that will quickly attain normal operating condition upon being lighted. 5

Another object of the invention is to provide a stove of the class described that will operate quietly, and with a steady fire that is readily responsive to adjustments of the control valve.

To these ends we form our burner bowl—or 10 the vaporizing parts or walls thereof—of relatively thin sheet metal so that, upon the fire being lighted, the vaporizing parts will quickly attain the high temperature necessary to vaporize the heaviest of oils suitable for use in the stove, and 15 in order to prevent the bottom of the bowl from being chilled by the air as it approaches the air inlets, we insulate the bottom portion of the bowl, preferably by applying one or more plates thereto in spaced relation to said bottom wall and to 20 one another so as to provide a like number of dead air spaces. This arrangement is peculiarly suited to our purpose because the insulating medium does not to any appreciable extent interfere with prompt heating of the relatively thin wall 25 of the bowl, yet it is more effective in preventing chilling of said wall by the air outside the bowl than solid insulation would be.

As a further means of protecting the burner bowl from the cooling influence of the incoming 30 air, we shield the bottom of the bowl by air directing and control means that deflects the rising air outwardly and away from the bowl and smooths it out into a relatively thin sheet in spaced relation to the peripheral wall of the 35 burner bowl. Besides protecting the bowl as aforesaid, this air directing and control means causes the burner to operate quietly and with an even or steady fire because it obviates excessive fluctuating pressures ordinarily resulting from 40 the invariable irregularities of the flue draft, wherefore the spasmodic action heretofore common in stoves of this class is eliminated. By reason of this effect, the burner responds more readily and accurately to valve adjustments, and 45 because the fire is more uniform and steady, the closure of the relatively large lighting and cleaning opening of the burner bowl may be removed at any time with safety.

The foregoing objects and advantages are attained in the embodiments of our invention illustrated in the accompanying drawings wherein Fig. 1 is a fragmentary sectional side elevation of a stove incorporating our improvements; Fig. 2 is a horizontal section on the line 2—2 of Fig. 1, 50 55

on a somewhat larger scale, looking upward; Fig. 3 is a view similar to Fig. 1 of a simplified form of the invention, this embodiment being suited to smaller stoves, and Fig. 4 is an enlarged section 5 on the line 4—4 of Fig. 3, looking upward.

In the form of the invention illustrated in Figs. 1 and 2, 1 represents the stove base that is supported a suitable distance above the floor by legs 2; and over an upstanding cylindrical part 3 of the base is engaged the lower end of a drum or casing 5, the parts being suitably connected together in accordance with common practice. The interior of the drum or casing 5 is divided into a combustion chamber 6 and a burner compartment 7 by a horizontal annular partition 8 which, in the present embodiment, includes a ring-like member 9 that is detachably connected to the outer part of the partition by fastening means or bolts 10.

20 Connected to and spaced from the underside of the partition 8 by fastening means or rivets 11 is the annular top wall 12 of the burner bowl 13. The inner edges of the partition and top wall 12 are turned downwardly, and the space 25 between these parts constitutes a secondary air inlet. The peripheral wall of the burner has rows of perforations 15 that serve as additional air inlets, essentially for primary air. Air is also admitted to the central region of the burner bowl through a tube 16 that opens through the bottom wall of the burner. A relatively large lighting and cleaning opening in the front portion 30 of the peripheral wall of the burner bowl is surrounded by a sleeve 17 that projects through an opening in the drum or casing 5 and is adapted 35 to be closed by a removable plug 18, the same being normally locked in place by a so-called bayonet joint consisting of an angular groove 20 that is formed in the side of the plug and opens 40 through the inner end thereof and is adapted to receive a projection 21 on the sleeve 17. The plug 18 is normally concealed by a door 23 that may be hingedly and removably connected at 45 24 to the top of the front leg of the stove.

45 Oil is delivered to a sump 25 in the bottom wall of the burner bowl 13 through a supply pipe 26 that leads from a valve 27, which, in turn, communicates with a distributing receptacle 28, over which a reservoir 29 is adapted to be sustained in inverted position by a carrier 30. The carrier is hingedly supported at 31 in operative relation to the receptacle and may be swung by means of a handle 32 from the position shown in the drawings to a reversed position rearwardly 50 of the stove so that the reservoir 29 may be placed therein and when the carrier is returned to upright position the reservoir 29 will be automatically inverted over the receptacle 28 and the stem of a valve 33 that controls discharge 55 of oil from the reservoir will engage an abutment in the bottom of the receptacle 28 thereby to unseat the valve and allow oil to flow from the reservoir into the receptacle to a depth sufficient to seal the reservoir. The rate of flow is 60 controlled by the previously mentioned valve 27 whose stem 35 projects above the top plane of the carrier 30 where it is equipped with an operating handle 36.

An annular flange 40 extends inwardly from 70 the top edge of the cylindrical part 3 of the base 1 and to this flange is secured, by fastening means or screws 41, a circular plate or diaphragm 42 that is shown as surrounded by a relatively deep flange 43. Mounted upon and welded or 75 otherwise secured to the plate or diaphragm 42

and desirably in concentric relation therewith and with the burner bowl 13 is an air baffle 45, the same flaring outwardly at a rather abrupt angle to the plate 42 from its point of connection therewith to where it terminates in a cylindrical portion 47. Rising in relatively closely spaced and concentric relation to the cylindrical portion 47 of the baffle 45 is a substantially cylindrical air guide 48 that is flanged inwardly at its lower end and rests upon the plate 42 to which it is suitably fastened, as by welding. Between the baffle 45 and the air guide 48, the plate 42 is provided with a circular series of holes 50, certain of which are provided with dampers 51, as is best shown in Fig. 2. It is the feature just described, involving the baffle 45 and the air guide 48, that has previously been referred to as the air directing and control means that deflects the rising air outwardly and away from the bowl and smooths it out into a relatively thin sheet in spaced relation to the peripheral wall of the bowl. Besides protecting the bowl from the cooling influence of the incoming air, this air directing and control means causes the burner to operate quietly and with an even or steady fire because it obviates excessive fluctuating pressures ordinarily resulting from the invariable irregularities of the flue draft, wherefore the spasmodic action heretofore common in stoves of this class is eliminated. By reason of this fact the burner 30 responds more readily and accurately to adjustments of the valve 27, and because the fire is more uniform and steady the plug 18 that constitutes the closure of the relatively large lighting and cleaning opening of the burner bowl may 35 be removed with safety at any time.

Applied to the bottom of the burner bowl 13 are insulator plates or shells 55 and 56, provided with apertures for the passage of the oil supply pipe 26, and with central air inlet openings that 40 register with the air tube 16, the plates or shells being otherwise imperforate so as to enclose dead air spaces, respectively, between the two plates and between plate 55 and the bottom wall of the burner bowl 13.

45 Preparatory to lighting the stove, the valve 27 is opened to permit oil to flow from the receptacle 28 to the sump 25 in the bottom of the burner bowl, and the door 23 is opened, and the plug 18 removed. The oil in the burner bowl is then 50 ignited by projecting a lighted match or taper into the bowl or by throwing into the bowl a piece of burning paper, after which the plug 18 is replaced and the door closed. Air enters through the inlet openings 15 to support initial 55 combustion and as the fire gets under way additional air is drawn in through the slot between the top wall of the bowl and the partition 8 and through the air tube 16. Soon after the fire starts, the side and bottom walls of the burner 60 bowl become heated sufficiently to vaporize the oil practically as fast as it enters the sump 25 from the pipe 26, and the size of the fire may be governed by the adjustment of the valve 27.

65 It is evident from the foregoing that all grades of oil at all suitable for use in the stove will perform in substantially the same way inasmuch as the oil is immediately converted into vapor which commingles with the incoming air to form a combustible mixture; and the rate of flow in all 70 instances is dependent upon the two factors, viscosity and valve adjustment, and the latter, being manually controlled, may be varied to compensate for differences in viscosity.

Air entering the burner compartment 7 through 75

the holes 50 is deflected outwardly and away from the burner bowl and upwardly into said compartment in a comparatively thin sheet, and by reason of the restricted space or throat between the adjacent cylindrical parts of the baffle 45 and the air guide 48, the air is sufficiently throttled to prevent its influx from being appreciably affected by differences in pressure resulting from variations in the chimney draft, it being understood that stoves of this class have flue connections with chimneys. A part of the air that enters the compartment 1 sweeps down beneath the burner bowl and enters the bowl through the air tube 16, and this or the surrounding air is prevented from having any cooling effect upon the bottom wall of the bowl by the dead air spaces provided by the insulator plates or shells 55 and 56.

In order to vary the air supply to the burner to meet possible differences in conditions encountered in different installations, and which may affect the operation of the stove, dampers 51 are provided for partially or completely shutting off certain of the holes 50 in the plate 42.

25 In describing the embodiment of the invention illustrated in Figs. 3 and 4, the same reference numerals, augmented by the letter *a*, will be used to designate the parts corresponding to those indicated by the same numerals in the embodiment shown in Figs. 1 and 2. As previously pointed out, the construction disclosed in Figs. 3 and 4 is especially suited to small stoves.

In this case, the plate 42^a is integral with the upstanding cylindrical part 3^a of the base 1^a. 35 Since, in the present embodiment, the drum or casing 5^a is of small diameter relative to that of the burner bowl 13^a, an air director, such as that designated 48 in the former embodiment, is omitted, and the cylindrical portion 47^a of the air baffle 45^a is arranged in closely spaced relation to the adjacent portion of the drum or casing 5^a to effect the narrow annular slot through which air, admitted through the holes 50^a, enters the burner chamber 1^a. In the present case, a single 40 insulator plate or shell, designated 55^a, is applied to the bottom of the bowl 13^a.

From the previous detailed explanation of the first described form of the invention, the remaining structural features, and the mode of operation, of the present embodiment will be 45 readily understood.

Having thus described our invention, what we claim is:

1. A stove of the class described comprising a 55 casing enclosing a combustion chamber and a burner compartment therebelow, a partition separating the chamber from the compartment and having a relatively large opening, an open top burner bowl sustained in the compartment with its open top in register with said opening and its rim in spaced relation to the partition, the bowl having air inlet means disposed circumferentially thereof and opening into said compartment, a diaphragm defining the bottom of the 60 burner compartment and having openings through which air is admitted to the compartment, air directing means associated with said air openings for distributing air about the burner bowl in outward spaced relation to the peripheral 65 wall thereof, an insulator shell applied to the bottom of the burner bowl, and means for delivering oil to the bowl.

2. In a stove of the class described, a structure enclosing a burner compartment including 70 a cylindrical wall, a cylindrical burner bowl situ-

ated substantially centrally thereof and having air inlet holes in its peripheral wall, a diaphragm defining the bottom of the burner compartment, the diaphragm having a circular series of air admitting openings, a baffle rising from the diaphragm inwardly of the series of openings and flaring outwardly over the same and thence upwardly in closely spaced relation to said cylindrical wall, damper means for controlling the passage of air through certain of said openings, 10 and means for delivering oil to the burner bowl.

3. In a stove of the class described, a structure enclosing a burner compartment including a cylindrical wall, a cylindrical burner bowl situated substantially centrally within said compartment and having air inlet holes in its peripheral wall, a diaphragm defining the bottom of the burner compartment, the diaphragm having a circular series of air admitting openings, and a baffle rising from the diaphragm inwardly of 15 the series of openings and flaring outwardly over said openings and thence upwardly in closely spaced relation to said cylindrical wall, an insulator shell applied to the bottom of the burner bowl, and means for delivering oil to the bowl.

4. In a stove of the class described, a casing enclosing a burner compartment, a cylindrical burner bowl situated within said compartment in materially spaced relation to the surrounding walls thereof, the burner bowl having air admitting openings in its peripheral wall, an air tube rising within and opening through the bottom wall of the bowl, a diaphragm defining the bottom of the burner compartment and having a circular series of holes for admitting air to the compartment, a baffle rising from the diaphragm inwardly of said series of holes and flaring outwardly and thence upwardly above the bottom plane of the bowl and in substantial outward spaced relation to the peripheral wall of the bowl, 30 and a cylindrical air director rising from the diaphragm outwardly of said series of openings in closely spaced relation to the upper end of the baffle, an insulator shell applied to the bottom of the bowl and having an opening through which 35 the air tube communicates with the compartment, and means for delivering oil to the bowl.

5. A stove of the class described comprising a casing enclosing a combustion chamber and a burner compartment therebelow, a burner bowl 40 in said compartment having an open top communicating with the combustion chamber, an insulator shell applied to the bowl in spaced relation to the bottom wall thereof, a diaphragm defining the bottom of the burner compartment, the same having a series of holes for admitting air to said compartment, an air director rising from said diaphragm outwardly of said holes, an air baffle surmounting the diaphragm inwardly of 45 said holes and having its upper end substantially parallel with and in closely spaced relation to the upper portion of said air director thereby to provide a restricted slot through which air admitted through said holes enters the burner compartment in a thin sheet, the air director and the 55 baffle being so related in size to the burner bowl as to dispose said sheet of air a material distance outwardly of the peripheral wall of the bowl, an air tube within the burner bowl in spaced relation to the peripheral wall thereof and 60 opening through the bottom wall of the bowl and through said insulator shell, and means for delivering oil to the bowl.

6. In a stove of the class described, a casing enclosing a burner compartment, a cylindrical 70

burner bowl situated within said compartment in materially spaced relation to the surrounding walls thereof, the burner bowl having air admitting openings in its peripheral wall, a diaphragm defining the bottom of the burner compartment and having a circular series of holes for admitting air to the compartment, a baffle rising from the diaphragm inwardly of said series of holes and flaring outwardly and thence upwardly above the bottom plane of the bowl and in substantial outward spaced relation to the peripheral wall of the bowl, and a cylindrical air director rising from the diaphragm outwardly of said series of openings in closely spaced relation to the upper end of the baffle, and means for delivering oil to the bowl.

7. A stove of the class described comprising a structure enclosing a combustion chamber and a burner compartment below said chamber, a

burner bowl within said compartment, the portion of the structure defining the bottom of the combustion chamber and the top of the bowl including a throat through which the bowl and chamber communicate, there being means for admitting air from said compartment to the burner bowl about the sides thereof and about said throat, a diaphragm forming the bottom of the burner compartment and having openings through which air is admitted to the compartment, air directing means associated with said air openings for distributing air about the burner bowl in outward spaced relation to the peripheral wall thereof, an insulator shell applied to the bottom of the burner bowl, and means for delivering oil to the bowl.

CHARLES J. KESSLER.
JOSEPH R. KIRKPATRICK.
